VANE PUMP

Warren R. Tucker and George A. Waldie, Dayton,
Ohio, assignors to The Hydraulic Development
Corp. Inc., Wilmington, Del., a corporation of
Delaware

Application February 6, 1941, Serial No. 377,709

5 Claims. (Cl. 103—136)

This invention relates to fluid pumps of the vane type, and more particularly to fluid pumps which are adapted for circulating liquids and for producing pressure with said liquids for actuating various operating elements.

In this invention the fluid pump is adapted to pump hydraulic fluid from a storage chamber to a hydraulically actuated device, such as a press, molding machine or other conventional hydraulically actuated mechanisms. There are many types of pumps which are adapted for placing fluids under pressure, including the radial piston type of liquid pump. This type of pump produces high pressure with relatively low power consumption and has been the most efficient type for use in producing high fluid pressures for actuating mechanical presses requiring high fluid pressures.

In this invention, however, mechanical alterations have been made to a vane type of fluid pump which makes it adaptable for producing high fluid pressures, and particularly, high liquid pressures which are of sufficient value that the pump can be used as the pressure supply mechanism for actuating hydraulic mechanisms. In former vane type pumps considerable difficulty has been encountered in producing high pressures, since the liquid slip past the vane has been considerable. There have been attempts to secure the vanes in constant engagement with the cylindrical wall of the cylinder and to increase the volumetric efficiency of vane type pumps when used for liquid delivery. These applicants have produced a mechanism which promotes the maximum efficiency of a vane type liquid delivery pump and which retains the vanes of the pump in constant engagement with the cylindrical wall of the cylinder to prevent liquid slip past the ends of the vanes which are in engagement with the cylinder wall.

It is an object of this invention to provide an improved pump structure for use as a liquid pump.

It is another object of the invention to provide means for retaining the vanes of a vane type pump in engagement with the wall of the cylinder.

It is another object of the invention to provide a mechanism in accordance with the foregoing object which resiliently urges the vanes outwardly into engagement with the cylinder wall.

It is another object of the invention to provide a vane type pump having a plurality of vanes wherein a cylindrical member engages the vanes in a manner that all of the vanes are

retained in constant engagement with the wall of the cylinder.

It is another object of the invention to provide a vane type liquid delivery pump having means for retaining the vanes in constant engagement with the walls of the cylinder, and which cylinder is adapted to be moved with respect to the pump rotor in order to change the direction of delivery of the pump.

10 It is another object of the invention to provide a variable delivery reversible flow liquid pump of the vane type having a mechanism for maintaining the vanes in engagement with the cylinder wall, and which is constructed and arranged for movement of the cylinder with respect to the rotor without affecting the mechanism for maintaining the vanes in constant engagement with the cylindrical wall of the cylinder.

20 Further objects and advantages will become apparent from the description and the drawings.

In the drawings:

Figure 1 is a longitudinal cross-sectional view taken along line 1—1 of Figure 2.

25 Figure 2 is a transverse cross-sectional view taken along line 2—2 of Figure 1.

Figure 3 is an enlarged partial cross-sectional view of one of the vanes of Figure 2, and particularly the vane indicated at A.

30 In this invention the fluid or liquid pump consists of a casing having passageways 11 and 12 extending therethrough. Outlet openings 13 and 14 are provided in the passageway 11, while outlet openings 15 and 16 are provided in the passageway 12. A substantially rectangular member 17 forms a cylinder block within which there is provided a cylindrical bore 18 which extends transversely of the block 17. This bore 18 forms the cylinder wall of the cylinder of the pump. The cylinder block 17 is carried between parallel faces 19 and 20 provided on the casing 10, the parallel faces provided on the cylinder block 17 slidably engaging the faces 19 and 20 to permit the cylinder block 17 to be reciprocated thereon. A passageway 21 provided in the cylinder block 17 communicates with the passageway 11, and a passageway 22 provided diametrically opposite the passageway 21 communicates with the passageway 12.

50 A rotor member 23 has a body portion 24 positioned within the cylinder bore 18. One side of the body portion 24 carries a flanged portion 25 which engages the wall of the cylinder block 17, as indicated at 26. An end plate 27 is secured to the rotor body 24 by means of the bolts 28 and

is adapted to engage the opposite face of the cylinder block 17, as indicated at 29.

The flanged portion 25 of the rotor 23 has a hub 30 extending therefrom which is carried by the inner race 31 of a ball bearing 32 which is positioned within a recess provided in the casing 10. The end plate 27 has a hub 34 which carries a bushing 35. The bushing 35 is carried by the inner race 36 of a ball bearing 37 mounted within a recess 39 of the end plate 40 of the casing 10. The end plate 40 is secured to the casing 10 by means of the bolts 41 and encloses the pumping mechanism within the casing 10. The hub 30, on the flanged portion 25, extends outwardly of the casing 10 and provides a drive shaft 42 which can be suitably connected to a driving mechanism, such as an electric rotor or any other suitable power device.

A conventional oil seal 43 is positioned around the drive shaft 42 and is retained within a recess 44 in the casing 10 by means of a closure plate 45.

The body 24 of the rotor 23 is provided with a plurality of radial slots 46 in each of which there is positioned a vane 47. The vanes 47 have their outward ends in engagement with the cylindrical bore 18 and which cooperate with the cylindrical bore 18 and the body of the rotor 24 to provide means for pumping fluid between the passageways 11 and 12. The vanes 47 have their inner ends extending within a central bore 48 provided in the rotor body 24. The bore 48 extends into the flanged portion 25 and a cooperating bore 49 is provided in the plate 27. The vanes 47 are all of equal length and since the cylinder bore 18 is eccentric with respect to rotor body 24 when the pump is in operating position, as indicated in Figure 2, it can readily be seen that the vanes 47 will extend into the bore 48 in the rotor body 24, and that the extending portion of each vane will have a different radial length according to the position of the vane with respect to the eccentric positioning of the cylinder bore 18 with respect to the rotor body 24.

In order to retain the vanes 47 in constant engagement with the cylinder bore 18 a cylindrical pin 50 is positioned within the bore 48 and is of such diameter that the cylindrical surface thereof engages each of the inner ends of the vanes 47. The ends of each of the vanes 47 have an arcuate contour, as indicated at 51, which arc is swung from the center point of the length of the vane so that the arcuate surfaces 51 are portions of a cylinder. Since the vanes 47 are all of equal length it can be seen that the cylindrical pin 50 will be arranged concentric with respect to the cylindrical bore 18, and since the end surfaces 51 of the vanes 47 have an arcuate contour which is a portion of a cylinder, it can readily be seen that the vanes 47 will remain in constant engagement with the cylindrical bore 18 at all points throughout their rotation about the pin 50. The pin 50 thus becomes a member which is floated by the inner ends of the vanes 47, which provides a rigid bearing surface upon which the vanes ride in order to mechanically urge the same into constant engagement with the cylindrical bore 18.

The cylindrical pin 50 is provided with a tapered surface which extends longitudinally thereof, as can readily be seen in Figure 1. The inner ends of the vanes 47 are also provided with a tapered surface which extends longitudinally of the vane. These tapered surfaces on the pin 50 and the vanes 47 cooperate, as indicated at 52, to provide surfaces by which the radial posi-

tion of the vanes 47 can be altered. Longitudinal or axial movement of the pin 50 forces the vanes 47 inwardly or outwardly according to the direction of movement of the pin 50 to thereby increase or decrease respectively the clearance between the end of the vanes 47 and the cylinder bore 18.

The adjusting means for axially or longitudinally moving the pin 50 consists of a cylindrical plunger 53 mounted within a bore 54 provided in the hub 30 of the rotor 23. The plunger 53 extends into the bore 49 within the body 24 of the rotor and engages the pin 50, as indicated at 55. A compression spring 56 is positioned between the end wall 57 of the plunger 53 and the end wall 58 of the bore 54, which spring tends to urge the tapered pin 50 to the right, as indicated in Figure 1. The taper on the pin 50 extends from the left to the right thereof, viewed in Figure 1, so that movement of the pin 50 to the right will tend to force the vanes 47 outwardly into engagement with the cylinder bore 18. The spring 56 thus provides means for resiliently urging the tapered pin 50 into pressure engagement with the vanes 47. A small hole 53a is provided in the end of the plunger 53 to prevent the plunger from acting as a piston.

An adjusting screw is provided in the end plate 27 and engages a friction button 60 which engages the right-hand end of the tapered pin 50. The adjusting screw 59 is in threaded engagement within the hub 34 of the end plate 27. An inspection plate 61 is provided on the end plate 40 of the casing 10 to permit access to the adjusting screw 59. Means for binding the adjusting screw in position after an adjustment has been made is provided on the hub 34 of the end plate 27 and consists of a portion 62 of the hub which has been separated from the main body thereof by means of a slot 63. A screw 64 extends through the portion 62 and into threaded engagement with the body of the hub 34. When the screw 64 is tightened the flanged portion 62 will bind upon the threads of the adjusting screw 59 to retain the same in its properly adjusted position. A drain opening 66 is provided in the casing 10 to remove liquid or fluid leaking into the casing from the pumping mechanism.

In the structure of the pump of this invention, it will be noted that the tapered pin 50 engages the tapered inner ends of the vanes 47 in such a manner that the spring 56 constantly urges the pin 50 in a direction that the vanes 47 are constantly urged in an outward direction. The adjusting means 59 which opposes the spring 56 engages the opposite end of the tapered pin 50 so that its movement in a rightward direction as viewed in Figure 1 is limited or controlled by the position of the button 60 as regulated by the adjusting screw 59. The force of the spring 56 urging the tapered pin in a rightward direction may thus be directly carried by the button 60 when the pin has moved the maximum amount as controlled by the face of the button.

By the arrangement thus disclosed, it is possible to use any desired spring pressure against the tapered pin 50 for holding the vanes 47 outwardly against the cylinder 21 and yet the exact degree of pressure that is directly applied to the vanes through means of the pin 50 is controlled or regulated by the adjusting means. The vanes are thus held against the surface 18 of the cylinder 21 with a substantially light pressure existing between the surface of the tapered pin 50

and the surface of the cylinder. However, movement of the vanes inwardly toward the center of the rotor is opposed by whatever pressure or force that is developed by the spring 56, so that the vanes 47 cannot collapse toward the center of the rotor until a pressure has been developed in the pump that is of sufficient quantity to cause inward movement of the vanes when applied upon the outer ends thereof to overcome the force of the spring. When such a high pressure is reached, the vanes 47 have complete freedom of movement inwardly to relieve this excess pressure and the tapered pin 50 can move in the leftward direction, as viewed in Figure 1, against the force of the spring 56 to leave engagement with the button 60 momentarily until the excess pressure has been relieved from the pump. As soon as the excess pressure is relieved the spring will again urge the vanes outwardly and retain them in this position with the major force of the spring being carried by the button, or adjusting means, so that the vanes can then run under light pressure between the tapered pin and the surface of the cylinder.

The mechanism just described provides a fluid or liquid pump wherein the fluid flow through the pump is an in-line flow, whereby minimum resistance to fluid flow is obtained and which provides a structural arrangement whereby the fluid can be circulated through the pump without the necessity of passing through a center pintle.

As heretofore described, the flange portion 25 and the end plate 27, together with the body portion 24 form a unit rotor which has the flange portions thereof in sliding engagement with parallel side wall faces 26 and 29 of the cylinder block 17. The unit rotor structure is carried between the ball bearings 32 and 37 in a manner whereby any distortion within the pump caused by production of high pressures therein will be carried directly by the bearings and not by any friction surfaces. While the surfaces 26 and 29 are in close engagement, yet there is always sufficient clearance between these faces to provide a film of lubricating oil therebetween. Any distortion within the pump due to the production of high pressure will be upon an axis at right angles to the axis of the supporting bearings 32 and 37, whereby the movement of the hubs 30 and 34 parallel to the axis of rotation thereof will be absorbed by the bearings 32 and 37, the end plates 25 and 27 merely slide parallel with respect to the engaging surfaces 26 and 29.

It is thus seen that this structure provides a pump which has a minimum of friction when developing high pressure and which can develop high pressure without slippage of fluid past the vanes since the vanes are retained in constant engagement with the cylinder bore 18.

The pump, as just described, can be operated as a variable delivery pump, or the fluid flow therethrough can be reversed. As previously described the cylinder block 17 is in sliding engagement with the surfaces 19 and 20 of the casing 10. The plane of eccentricity of the cylinder bore 18 with respect the rotor 23 is parallel to these surfaces 19 and 20 so that reciprocation of the cylinder block 17 parallel to the surfaces 19 and 20 alters the eccentricity of the cylinder bore 18 with respect the body 24 of the rotor. If the cylinder block 17 is shifted from left to right, as viewed in Figure 2, the direction of flow of fluid through the pump will be reversed even though the rotation of the rotor remains continuously in

the same direction. Plungers 65 extend through opposite side walls of the casing 10 and engage opposite walls of the cylinder block 17. These plungers are connected to suitable control mechanisms for altering the position of the cylinder block 17 with respect the rotor body 24. These control mechanisms may be responsive to the discharge pressure from the pump or can be responsive to mechanisms which indicate the requirement for a reverse of fluid through the pump. However, such mechanisms are common and are well known in the art of variable delivery and reverse flow pumps and therefore further description thereof is not believed necessary since

10 the particular mechanism forms no part of this invention and since any of the well known devices can function to operate the plungers 65 to either vary the flow through the pump or reverse the flow through the same.

15 20 While the form of the pump heretofore described is a preferred form, yet there are mechanical modifications thereof which can be developed, and we desire to comprehend within our invention these various mechanical modifications.

25 30 Having thus fully described our invention, what we claim as new and desire to secure by Letters Patent is:

35 40 1. In a pump, a cylinder, a rotor rotatable therein, reciprocable vanes carried by the rotor, means within said rotor to cause the vanes to maintain constant engagement with the inner wall of said cylinder while reciprocating in and moving bodily with said rotor comprising a tapered pin in engagement with the inner ends of said vanes, resilient means carried in said rotor acting against the larger end of said pin for constantly forcing said pin in a direction to move the vanes outwardly, and adjustable means carried by said rotor acting against the smaller end of said pin to limit the maximum movement of the pin in said direction.

45 50 55 2. In a pump, a cylinder, a rotor rotatable therein, reciprocable vanes carried by the rotor, means within said rotor to cause the vanes to maintain constant engagement with the inner wall of said cylinder while reciprocating in and moving bodily with said rotor comprising a tapered pin in engagement with the inner ends of said vanes, resilient means carried in said rotor acting against the larger end of said pin for constantly forcing said pin in a direction to move the vanes outwardly, and a screw carried by said rotor engaging the smaller end of the tapered pin to limit the movement of the pin and thereby determine the maximum amount of resilient force applied through the pin to the vanes.

60 65 70 75 3. In a pump, a cylinder, a rotor rotatable therein, reciprocable vanes carried by said rotor, means within said rotor engaging said vanes to cause the vanes to maintain constant engagement with the inner wall of said cylinder while reciprocating in and moving bodily with said rotor comprising a tapered pin in engagement with the inner ends of said vanes, resilient means carried in said rotor for continuously acting against said pin for constantly forcing said pin in a direction constantly urging the vanes outwardly against said cylinder, and adjustable means carried by said rotor for opposing the movement of said pin as caused by said resilient means to limit or control the maximum movement of the pin in the said direction as caused by said resilient means.

4. In a pump, a cylinder, a rotor rotatable therein, reciprocable vanes carried by said ro-

tor, means within said rotor engaging said vanes to cause the vanes to maintain constant engagement with the inner wall of said cylinder while reciprocating in and moving bodily with said rotor comprising a tapered pin in engagement with the inner ends of said vanes, resilient means carried in said rotor for continuously acting against said pin for constantly forcing said pin in a direction constantly urging the vanes outwardly against said cylinder, and adjustable means engaging said pin to oppose the motion thereof as caused by said resilient means to limit the maximum movement of said pin as caused by said resilient means, said pin being movable away from engagement with said adjusting means against the urge of said resilient means to permit said vanes to move inwardly toward the center of said rotor to relieve excess pressure conditions in said cylinder.

5. In a pump, a cylinder, a rotor rotatable 20

therein, reciprocable vanes carried by said rotor, means within said rotor engaging said vanes to cause the vanes to maintain constant engagement with the inner wall of said cylinder while reciprocating in and moving bodily with said rotor comprising a tapered pin in engagement with the inner ends of said vanes, resilient means carried in said rotor for continuously applying a determined force upon said pin for constantly forcing said pin in a direction to move the vanes outwardly against said cylinder, and adjustable means engaging said pin to oppose the motion thereof to control the maximum movement of said pin in said direction and thereby control the maximum pressure applied by said resilient means to said vanes for holding the same in engagement with said cylinder.

WARREN R. TUCKER.
GEORGE A. WALDIE.
